UNITED STATES PATENT OFFICE.

CHARLES F. SMITH, OF NEW BRITAIN, AND SVEND J. HELWEG, OF HARTFORD,
CONNECTICUT.

DESIGN FOR A WASHING-MACHINE CASING.

Application filed September 14, 1926. Serial No. 19,069. Term of patent 3½ years.

To all whom it may concern:

Be it known that we, CHARLES F. SMITH and SVEND J. HELWEG, citizens of the United States, and residents of New Britain and Hartford, respectively, county of Hartford, State of Connecticut, have invented a new, original, and ornamental Design for a Washing-Machine Casing, of which the following is a specification, reference being had to the accompanying drawing, forming part thereof.

In the accompanying drawing:—

The figure is a perspective view of a washing machine casing showing our design.

We claim:

The ornamental design for a washing machine casing, as shown.

CHARLES F. SMITH.
SVEND J. HELWEG.
